LIQUID DISPENSING DEVICE

David Samiran, Fairfield, Ohio

Application April 24, 1940, Serial No. 331,366

9 Claims. (Cl. 210—54)

(Granted under the act of March 3, 1883, as
amended April 30, 1928; 370 O. G. 757)

The invention described herein may be manufactured and used by or for the Government for governmental purposes without the payment to me of any royalty thereon.

This invention relates to devices for dispensing liquid petroleum products, such as gasoline or other fuel for use in internal combustion engines, whereby such liquid may be dispensed in a rapid and continuous manner from a reservoir, forming a source of liquid supply, to a tank or other receptacle to be filled.

A tank or reservoir of liquid petroleum product frequently contains, in addition to the liquid petroleum product, water and a petroleum emulsion which is lighter than the water but heavier than the liquid petroleum product. Such an emulsion may be, for example, a heavier constituent formed in the manufacture or during the storage of the liquid petroleum product, or a constituent of intermediate specific gravity formed by the action of the water or liquid petroleum product upon the tank or reservoir. In the dispensing of a liquid petroleum product from a tank or reservoir, this water and petroleum emulsion become entrained in the liquid petroleum product and are dispensed therewith. This is always objectionable and particularly so in respect to gasoline or other liquid petroleum product to be used in airplane engines.

Among the objects of the present invention are to provide a device adapted continuously to dispense at a high rate of flow a liquid petroleum product in a manner such as to separate entrained water and petroleum emulsion therefrom while the liquid petroleum product is being dispensed.

A further object is to provide means for closing the dispensing line to prevent the separated water and/or petroleum emulsion from being discharged from the dispensing line with the liquid petroleum product.

Still another object is to provide a first float control means which is buoyant in water and not in the liquid petroleum product or in an emulsion of the liquid petroleum product, for discharging the water only, and an additional float controlling means which is sensitive to the petroleum emulsion but not to the liquid petroleum product itself, whereby to cause the closure of the dispensing line in the presence of a definite accumulation of petroleum emulsion in the fuel being dispensed.

Still another object is to provide a device for dispensing gasoline and similar liquid fuels in a rapid, continuous manner at a rate of approxi-

mately 210 gallons a minute, through a three-inch discharge line, while preventing water or petroleum emulsion entrained in the gasoline from being discharged through the line; and to provide these and other objects of invention as will be apparent from a perusal of the following specification when taken in connection with the accompanying drawings, wherein

10 Figure 1 is a side view of a truck or trailer equipped with my invention;

Figure 2 is a cross sectional view through the water separating, discharging device, showing the float in lower position;

15 Figures 3 and 4 are corresponding views showing the float in correspondingly different positions;

Figure 5 is an enlarged sectional view taken through the device;

20 Figure 6 is a view on the line 6—6 of Figure 5;

Figure 7 is a fragmentary view of the central portion of Figures 5 and 6; and

Figure 8 is a portable device embodying the invention.

Referring now to the drawings in detail, I have 25 shown a container forming a tank or reservoir 2 (Fig. 1) for holding a relatively large quantity of liquid petroleum product, such, for instance, as gasoline, and from this tank the gasoline is drawn through a dispensing flow line having a portion or conduit 4 connected to the tank and to a device 6 from which the liquid petroleum product is drawn through the dispensing line portion or conduit 8 by means of any desired pump 10. On the discharge side of the pump is located a meter 12 of any desired description, which discharges into a continuation of the flow line, herein shown as a flexible hose 14 terminating in a valve controlled nozzle 16 of the usual type.

30 In the present invention the reservoir 2 is preferably shown as forming the body portion proper of a trailer or truck having a relatively large fill opening 18 and mounted on wheels 20, whereby the tank 2 may be drawn to a remote location for filling the tanks of airplanes and the like, or for filling underground tanks, if desired.

35 The device has other adaptations than as applied to a truck or trailer, since it may be installed in most any type of device dispensing petroleum products free of water and/or petroleum emulsion.

40 The mechanism within the housing of the device 6 is shown in detail in Figures 5 and 6 and diagrammatically illustrated in Figures 2 to 4. It 45 comprises an outer shell or casing 22 having an inlet 24 and a discharge outlet 26 suitably

formed for connection to the conduits 4 and 8 of the dispensing line as shown in Figure 1.

In Figures 2, 3 and 4 the inlet conduit 24 is shown as formed with walls gradually curving, so that a centrifugal force is exerted upon the liquid as it is drawn by means of the pump 10 from the tank 2 into the casing 6, this centrifugal force causing water or petroleum emulsion entrained in the incoming liquid petroleum product, to be thrown downwardly along the bottom portion of the inlet 24. The gasoline, being lighter, will flow inwardly at a somewhat higher elevation. It is understood, of course, that complete separation by stratification is not attained, but there is a tendency toward stratification sufficient to cause the entrained water and emulsion, if present, to move outwardly and to be more localized at the lower portion of the inlet 24 than at the upper portion.

The casing 22 is formed substantially centrally 20 of its top with a rather large fluid outlet 28 which connects with a laterally extending fluid discharge passage 30 joining the conduit 8. Concentric with the outlet passage 28 is a vertical, elongated float chamber 32 having cylindrical walls which are provided with a plurality of relatively large ports 34 in their upper portions, to permit passage of petroleum product fuel from the space surrounding the cylindrical walls 32 inwardly through these ports, thence outwardly through port 28. The port 28 is provided at its upper portion with an inclined valve seat 36.

Concentrically surrounding the float chamber 32 and mounted within the casing 22 is a cylinder 38 which is provided with a downwardly inclined bottom 40 and peripheral, vertical walls 42 which make liquid-tight connection with the top 44 of the casing 22. The walls 42 are formed of wire mesh screen of from 50 to 100 mesh to the inch, and there are plurality of reinforcing strips 46 and 48 for stiffening the screen and holding it in position. The bottom member 40 is fastened to a central casting 50.

The casting 50 forms a part of the bottom of the float chamber 32. A somewhat similar casting 52 is bolted to the main casting 50 and forms a downward extension thereof. These two castings 50 and 52 are provided with registering bores forming a liquid inlet to the chamber 32.

The bottom member 40 is provided at portions remote from the inlet 24 with openings 54, and a screen 55 overlies member 40 and the openings 54. If desired, a lower portion of the wall 24 of the outer casing may be provided with an observation window 56 suitably bolted in place, as by means of bolts 58.

The lower portion of the fitting 52 is provided with an elongated pipe extension 60 which curves downwardly and is formed at its outer end with an open-mouth horn or nozzle 62 disposed at the bottom of the inlet 24 and directly facing the inlet, whereby it is directly within the influence of the inrushing liquid petroleum product pumped from the reservoir 2 by means of pump 10. The height of this horn 62 at its mouth is relatively small in proportion to the diameter or height of the inlet opening 24 so that only a portion of the liquid passing through the inlet will enter the mouth of the horn 62. However, the horn, at its mouth, extends completely across the inlet 24 in a horizontal direction as seen in Figure 6.

It will thus be seen that, since the mouth of the horn 62 extends across the bottom of the chamber 24, and the liquid as it enters the inlet is subjected to a somewhat centrifugal force,

there will be a tendency for the water and/or petroleum emulsion, which are heavier than gasoline, to be thrown downwardly toward the bottom of the inlet 24 and enter the horn 62. Therefore, the relatively small body of liquid entering the mouth or horn 62 will contain a greater proportion of entrained water and/or emulsion than the main body of liquid passing above the horn. The conduit 60 directs this relatively small body of liquid into the chamber 32 through the registering passages of the fittings 50 and 52. If no water or petroleum emulsion is present in the liquid petroleum product, only the petroleum product itself will flow through the mouth of horn 62 and through the conduit 60.

It will be noted that as the stream of petroleum product leaves the inlet 24, it is spread out laterally through the entire horizontal cross section of the casing and is directed thereacross by means of the baffle wall 40. The entering liquid petroleum product flows entirely across the bottom portion of chamber 38 within the casing 22, and also flows upwardly along the screen wall 42. During this travel across the bottom baffle 40, the liquid is slowed down substantially to one-half of its entering velocity. In other words, the originally fast moving column of liquid petroleum product now traverses the chamber at a substantial reduction in speed, and then passes through the fine-mesh screen walls 54 and 42, which are from 50 to 100 mesh per inch, whereby to remove entrained water therefrom. The liquid petroleum product then passes through the ports 34, past the valve seat 36 and the discharge port 28, into the outlet 30, and thence through the flexible hose 14 to be discharged through the nozzle. A portion only of the liquid may pass upwardly through the screened bottom walls 54 relatively close to the fittings 50 and 52. As the liquid passes through the relatively large ports 34, it will move with considerable velocity toward the outlet 28.

Disposed within the float cylinder 32 is a relatively large float 64 preferably formed of two metal sections suitably joined together to form an enclosed, sealed, relatively hollow member having a central, tubular, hollow sleeve 66 adapted to slide vertically on a circular guide 68 rigidly upstanding from a base 70 bolted to the bottom fitting 50. The base 70 is formed as a spider providing a series of openings 72 by which liquid may flow from the port 74 in the bottom casting 50 of the cylinder 32 into the float chamber 76 between the bottom wall of the float chamber and the bottom of the float. This liquid, or petroleum product, when the pump is in operation, flows upwardly between the outer wall of the float and the inner wall of the float chamber 32. Thence it passes upwardly and joins the column of liquid entering the upper portion of the float chamber through the ports 34, discharging with the liquid through the outlet 28.

The float is provided with a separate valve portion 78 suitably welded around its edge to the top of the float and formed with sloping sides 82 to engage the inclined walls of the valve seat. The central portion of the top of the valve is provided with a plugged port 84 which, when open permits the float to be filled with oil that flows from this port 84 through a cross port 86, thence downwardly through openings 88 in the top of the float.

The float is ballasted by this oil so that the float will lie in water up to the line marked 90 on the float. This float thus ballasted is buoyant in

petroleum emulsion and the ballast is such, in relation to the size of the passageway between the float, when in a lower position, and the float chamber, that liquid petroleum product passing upwardly through this passageway, causes no movement of the float. However, when petroleum emulsion or water enters the lower portion of the float chamber and in rising upwardly through this passage approaches the line marked 90, the float begins to rise. As the top of the float approaches the inwardly extending portion 92 and the float passes into this portion, it forms a restriction in the portion of the passage through which the liquid has been flowing, whereby the velocity of the flowing column of liquid petroleum product is increased. The liquid at this increased velocity accelerates the upward movement of the float and causes the float to rise ahead of the rise in level of the petroleum emulsion or water, whereby thus to position the top of the float more quickly within the zone of influence of the inwardly moving stream of liquid passing through the ports 34 into the port 28. The suction pressure at the port 28 and the stream of liquid flowing through the ports 34 cause the float to move still more rapidly upwardly and cause the valve on the top of the float to close upon its valve seat. By this means any possibility of petroleum emulsion or water passing through the outlet port 28 is precluded.

In certain instances I may desire to alter the cross-sectional area of the ports 34, whereby to cause a greater pull on the liquid entering the chamber 32 through lower openings 72 to assist in causing the float to rise. This is accomplished by a sleeve 94 which is slideable vertically along the float chamber walls 32 and held in any desired position of adjustment by means of a screw 96.

By reason of the foregoing construction, it will be appreciated that, as the liquid petroleum product enters the inlet port 24 at relatively high velocity—and in the present case this device is adapted to discharge gasoline or similar petroleum product through a three-inch pipe at a rate of approximately 210 gallons per minute—and as the petroleum product spreads across the lower portion of the casing 22, its velocity will be reduced substantially one-half and, due to the baffle plates, it will be directed thereacross and thence upwardly through the screens, at which speed the water will not pass the screens of such fine mesh and will be automatically separated therefrom. The now relatively slowly flowing gasoline or petroleum product will flow inwardly and pass through the upper openings 34 of the float chamber and thence through the discharge opening 28 and out the dispensing line.

In order to preclude any possibility that entrained water or petroleum emulsion might be carried along with the incoming liquid petroleum product and be discharged through the valve port into the outlet therewith, I have provided means for continuously conducting a portion of the incoming liquid, preferably a portion which has a larger percentage of entrained water and/or petroleum emulsion therein, at substantially the same speed as the incoming liquid, prior to its deceleration directly to a float controlled cylinder which is arranged or ballasted to be sensitive to water and/or petroleum emulsion. In the presence of either water or petroleum emulsion, the float will be raised, as hereinbefore described, and thereafter quickly close the valve in a manner such that no petroleum emulsion or water

carried by the incoming liquid petroleum product can reach the valve port before the valve closes upon its seat.

The water entrained in the liquid petroleum product which is flowing at slow speed, will not pass the fine mesh screens and hence will be separated out and will travel downwardly by gravity to the bottom of the chamber 22, and into a basin or chamber 98 suitably bolted, as at 100, to the bottom of this casing 22. This bottom of casing 22 slopes downwardly toward chamber 98 so as to direct the water thereinto.

The center portion of this chamber 98 is directly coaxial with the center axis of the upper float chamber 32, and in this chamber 98 I provide a float chamber formed by a concentric casing having a bottom wall 102 and having a vertically extending screened side wall 104, the screen of which is from 50 to 100 mesh per inch. A top wall 106 closes the top of the screen wall 104.

A central fitting 108 is adapted to clampingly engage within an aperture 110 in the bottom of the basin 98. This fitting 108 is centrally screw threaded to receive another fitting 112 centrally apertured to provide a water discharge conduit 114 which at its bottom extends laterally, as at 116, to connect with a pipe 118 extending upwardly at 120 to discharge the water outside of the system. This pipe 118 is provided with a control cock 122.

Within the upper portion of the fitting 112 there is a valve seat 124. The upper portion of the fitting 108 is provided with an upstanding tubular guide 126, around which is snugly fitted a hollow, central tube 128 of a float 130, whereby the float may rise and fall vertically. The hollow guide 126 is adapted to receive a centrally disposed needle valve 132 adapted to seat upon the valve seat 124. The upper portion of the needle has soldered thereto an open ended sleeve 134 within which fits a spring 136, the upper end of which takes against a plate 138 carried by the upper portion of the float 130. The upper end of the needle valve 132 is of reduced cross-section and passes freely through an opening in the plate 138 which is adapted to be engaged by adjusting nuts threaded on the upper end of the needle valve. By this means the spring normally holds the needle valve under sufficient tension to hold the valve on its seat against any movement of the float due to agitation or vibration, but permits the float to rise under the buoyant effect of a liquid of sufficient specific gravity. This float is hollow and is of two-piece construction and is formed with filling openings 140 by which it may be filled with any desired type of medium to cause it to float in water, but not in petroleum emulsion or gasoline or similar liquid petroleum product.

To the side of the central fitting, the bottom wall of the float basin 98 is provided with a threaded plug 142 controlling a port which, when opened, will permit the entire interior of the device to be flushed with water. To this end the upper portion of the discharge outlet 30 is provided with a filling plug 144 to permit water to be supplied thereinto for flushing the screens, the float, and the valves, to remove sediment, etc.

By reason of the foregoing construction, it will be appreciated that, as the liquid petroleum product enters the inlet port 24 at relatively high velocity, it will at once spread out across the bottom of the relatively large casing 22. The baffle 40 will direct the flow downwardly, whereby to prevent the petroleum product from pass-

ing upwardly around the entering side of the screen wall 42, and will direct the incoming petroleum product in a generally horizontal layer across the complete cross-sectional area of the lower portion of the casing 22 to the opposite side of the casing, at which point this incoming liquid will be directed upwardly and will thence pass through the opposite screen wall 42 into the chamber surrounding the float cylinder 32.

During this horizontal flow of the petroleum product as it expands into the larger chamber 22, its velocity is reduced or decelerated to substantially one-half its entering velocity, and therefore at this relatively slower speed, the entrained water will be separated by the screen walls of the chamber 38 so that the petroleum product, freed of such entrained water, thence passes inwardly through the upper ports 34, into the upper portion of the float cylinder 32, thence across the valve seat 36, out the discharge port 28, and through the outlet conduit 30 forming a continuation of the dispensing line.

Thus there is created within the float chamber 32, above the lowermost position of the float 64, a flow of liquid through the ports 34 and past the valve seat 36 at a considerable velocity. If the incoming petroleum product contain entrained water, then during the horizontal decelerated flow of this petroleum product, as above described, a portion of the water will have opportunity to separate by gravity, and this portion will immediately flow downwardly into the float basin 98. In addition, the entrained water, which is separated from the more slowly flowing stream of petroleum product by the screens 38, will gravitate vertically downwardly and will be directed by the downwardly inclined walls of the basin 98 into the lowermost portion of the basin where this water will accumulate and will pass through the screen 104 into the float chamber of the lower float controlled unit so that, when a sufficient quantity of this water has accumulated, it will raise the float and the needle valve, letting the water discharge into the water discharge passage 114, whence it will be gradually discharged through the water discharge nozzle 120. Inasmuch as this float is of sturdy construction and is buoyant only in water, no petroleum product will be discharged, and when the accumulated water level has dropped to a predetermined point, the float will immediately close to preclude the further discharge of water. Hence, this float will rise or fall, depending upon the accumulation of water present, and will continue automatically to discharge the water while the dispensing operation is in progress, due to the fact that the suction of the pump 10 is of greater capacity, or rather, is of sufficient capacity so that the water discharge will continue to function during the operation of this pump and during the continuous flow of petroleum product through the separating device.

If the liquid petroleum product entering the casing 22 through the port 24 at relatively high velocity should contain entrained petroleum emulsion, which must not be delivered through the dispensing line to the tank of the airplane or other tank, the delivery of such emulsion through the dispensing line is prevented. As hereinbefore described, the means for accomplishing this specifically comprises the upper float control device which is more sensitive than the lower float control device. The upper device is buoyant in, or sensitive to, petroleum emulsion but not to liquid petroleum product. It is also sensitive to

water. Petroleum emulsion is heavier than liquid petroleum product. Since the petroleum emulsion is present in a greater proportion at the lower portion of the incoming, downwardly directed stream, the liquid which is delivered to the upper float control device through the gathering device has a relatively greater percentage of emulsion than the liquid in the other parts of the separating device 6 outside of the chamber 34.

Water also will be present in a greater proportion at the lower portion of the incoming, downwardly directed stream, and similarly, therefore, the liquid which is delivered to the upper float control device has a relatively greater percentage of water than the liquid in the other parts of the separating device 6, outside of the chamber 34. Hence, the emulsion and/or water separated from the liquid petroleum product in the chamber will rise in level therein at a greater rate than the emulsion and/or water separated from the liquid petroleum product in the separator outside of the chamber 34.

The quick raising of the float 64 is therefore due to the combined effect (1) of the entrained constituents of heavier specific gravity than the petroleum product; (2) of the petroleum product flowing through the passage between the float and the inner wall of the float cylinder, and (3) of the petroleum product flowing through the ports 34 into the outlet port 28. As the heavier fluids enter and accumulate in the cylinder 32 to a predetermined level, the float rises so that it is adjacent or within the inwardly projecting flange of the upper wall of the cylinder and thereby creates a restricted passage, which causes the flow of petroleum product past the float to be accelerated. The petroleum product at this increased velocity of flow effects a quick raising of the float relative to the heavier fluids and into the zone of influence of the petroleum product passing through ports 34 into port 28. The petroleum product passing through ports 34 into port 28 at a relatively high velocity then effects a further and more rapid raising of the float relative to the heavier fluids and moves the float quickly to valve closing position.

In the event that petroleum emulsion and/or water should accumulate in a slight amount within the bottom portion of the float cylinder 32, that is, in an amount insufficient to raise this float, then upon the termination of the dispensing operation, the water and/or petroleum emulsion present therein will drain downwardly through the gathering device into the lower basin 98, whence the emulsion and/or water, or the water constituent of the petroleum emulsion, will stratify out in this basin.

It will be appreciated that I have provided a very sturdy float controlled mechanism for the lower level, whereby to insure the automatic discharge of water during the dispensing operation, while precluding the discharge therethrough of petroleum product or petroleum product emulsion. In addition, by making the lower float very sturdy and buoyant only to water, I am enabled to provide an extremely sensitive upper float which is buoyant only to petroleum product emulsion and not to petroleum product itself, and which upper float provides a very sensitive control for immediately stopping or closing the dispensing line in the presence of the suitable volumes of entrained water and/or petroleum product emulsion which might otherwise be discharged with the petroleum product and, in addition, by providing the foregoing arrangement,

in the event that the lower float control mechanism should become inoperative, as by freezing of the separated water, the upper control mechanism will still be operative to stop or close the control line in the presence of entrained water, whereby to preclude the passage of this water through the dispensing line.

In my application Serial No. 323,560, filed March 12, 1940, I have shown a construction similar to the portion 92 for accelerating the movement of the float upwardly, whereby to insure that the valve closes prior to the passage of water through the outlet ports, and I have claimed the same in such application, and therefore do not claim such subject-matter broadly except in so far as it enters into combination with the subject-matter of the present application. The construction of the present application does show, however, another adaptation of the invention claimed in my prior mentioned application inasmuch as the present device shows a means for increasing the discharge capacity of a device shown in my prior application, by increasing the size of the outlet port 28 and the size of the ports 34.

In Figure 8 of the drawings I have shown a further adaptation of my invention as applied to a portable unit adapted to be connected to a tank 150. In this device the segregator is identical with the segregator system shown in Figure 1 of the drawings except that it is mounted on a portable carriage 152 having wheels 154 and a supporting stand 156 and is provided with a flexible hose 158 and a manifold connection 160 adapted to be connected to a plurality of outlets from the different sources of supply, such as the various tanks of the tank truck 150. Each one of these outlets is provided with its own control valve 162 whereby the contents of the separate tanks may be discharged at will through the flexible hose 158 into the segregator 6, out through the pump 10, and out through the hose 14 formed with the valve operated dispensing nozzle 16.

Having thus described my invention, what I claim as new and desire to secure by Letters Patent is:

1. In a device of the class described, in combination with a reservoir for liquid petroleum product which may contain entrained liquid of greater specific gravity, means forming a dispensing line including a conduit connected to said reservoir, means associated with said line and reservoir for causing the liquid petroleum product to flow from said reservoir through said dispensing line, the liquid of greater specific gravity entrained in said liquid petroleum product flowing from said reservoir into said conduit with the liquid petroleum product, a casing forming a part of said dispensing line, said casing having an inlet passage connected to said conduit, a float receiving shell in said casing, means forming a common outlet passage from the upper portion of said shell and said casing, said shell having a main inlet passage in the upper portion thereof and having an imperforate portion below said outlet passage, a float in said shell and adapted, when raised, to fit said imperforate portion with slight clearance, a conduit connected to said outlet passage for delivering the liquid petroleum product from said casing, a valve carried by said float for opening and closing said outlet passage, said shell having an inlet opening in its lower portion, means for causing the

liquid petroleum product and the entrained heavier liquid in said casing to pass into said shell through said inlet opening, said inlet opening being relatively small compared to said main inlet passage, means for varying the size of said main inlet passage and means for discharging from said casing, the heavier liquid settling in the bottom thereof.

2. In a device of the class described, in combination with a reservoir for liquid petroleum product which may contain entrained liquid of greater specific gravity, means forming a dispensing conduit, means associated with said conduit and reservoir for causing the liquid petroleum product to flow through said dispensing conduit, the entrained liquid of greater specific gravity flowing from said reservoir into said conduit with said liquid petroleum product, a liquid separator forming a part of said conduit and comprising an outer casing having an inlet port, a second inner casing within said outer casing and small relative to the outer casing, means forming a discharge passage extending from the upper portion of the inner casing and out of the outer casing, said inner casing having in its upper portion a main inlet port through which the liquid petroleum product passes into the inner casing and toward the discharge passage, a float in said inner casing, means operated by said float for closing and opening said discharge passage as the float rises and falls, said float being responsive to the liquid of greater specific gravity but not to the liquid petroleum product, a conduit leading to said inner casing and terminating adjacent the lower portion of said outer casing to permit the liquid of greater specific gravity to pass into said inner casing from said outer casing and accumulate beneath said float to raise said float, means associated with the float and positioned by the float to variably restrict the stream of liquid petroleum product as it flows through said main inlet port toward said discharge passage whereby to vary the speed of rise of said float relative to the rate of flow of the heavier liquid into said inner casing, and means for discharging from said outer casing, the separated liquid of greater specific gravity.

3. In a fluid segregating system, a reservoir for liquid petroleum product which may contain entrained liquid of greater specific gravity, a liquid segregator comprising a casing having an inlet port connected to said reservoir and having a discharge port, a valve in said segregator for controlling the opening and closing of said discharge port, a delivery conduit connected to said discharge port, means associated with said reservoir and segregator for causing the liquid petroleum product to flow from said reservoir to said segregator and from said segregator through said conduit at a relatively high velocity, the entrained liquid of greater specific gravity flowing from said reservoir into said segregator with the liquid petroleum product, means forming a float receiving and liquid separating chamber within said segregator, said chamber having openings to receive liquid from said casing, the upper portion of said chamber being in communication with said discharge port and the lower portion of said chamber having an inlet port, a float in said chamber and connected to said valve for operating said valve, means in said segregator for dividing the stream of liquid entering said segregator through said inlet port into two portions, one a main portion and the other a relatively small por-

tion, said dividing means comprising a conduit leading to the inlet port in said chamber from the lower part of said casing to cause the small portion of the divided stream, more heavily charged with the entrained heavier liquid than the main portion of said stream, to enter said conduit and chamber and said segregator and conduit being of such size relative to each other as to decelerate the main portion of the stream sufficiently to separate the heavier liquid from the liquid petroleum product while delivering the small portion of the stream to the inlet port of said chamber at a higher rate whereby to cause the float in said chamber to be moved upwardly at a greater rate than the rate at which the heavier liquid separated from the main portion of the stream rises in level in the segregator outside of said chamber, and means for discharging from said casing, the heavier liquid settling to the bottom thereof.

4. In a liquid dispensing apparatus, a reservoir for liquid petroleum product which may contain water and a petroleum emulsion of specific gravity less than water but greater than the liquid petroleum product, a liquid segregator comprising a casing having an inlet port connected to said reservoir and having a discharge port, a valve in said segregator for controlling said discharge port, a dispensing conduit connected to said discharge port, means associated with said reservoir and segregator for causing the liquid petroleum product to flow from said reservoir to said segregator and from said segregator through said conduit at a relatively high velocity, entrained water and petroleum emulsion flowing from said reservoir to said segregator with the liquid petroleum product, means forming a float receiving and liquid separating chamber in said segregator, the upper portion of said chamber being formed with an opening positioned to establish communication with said discharge port and having below said opening, another opening for receiving liquid from said casing, the lower portion of said chamber having an inlet port establishing liquid communication with said segregator outside said chamber, a float in said chamber and connected to said valve for operating said valve, means in said segregator for dividing the stream of liquid entering said segregator into two portions, one a main portion and the other a relatively small portion, the segregator being constructed to cause the small portion of the stream to be more heavily charged with entrained water and petroleum emulsion than the main portion of the stream, said segregator and dividing means being so constructed and arranged as to decelerate the main portion of the stream sufficiently to separate the water and emulsion from the liquid petroleum product while delivering the small portion of the stream to the inlet port of said chamber at a higher rate whereby to cause the float to be moved upwardly at a greater rate than the rate at which the separated emulsion outside the chamber rises in level, said segregator having a water discharge port, a second float in said segregator beneath said first mentioned float chamber, said second float being buoyant to water but sinking in the liquid petroleum product and the petroleum emulsion, and means actuated by said second float for controlling the opening and closing of said water discharge port.

5. In a liquid dispensing apparatus, a reservoir for liquid petroleum product which may contain an entrained liquid of greater specific gravity, a segregator comprising a casing having inlet and

outlet ports, a dispensing line having a portion connected to said reservoir and to the inlet port of said casing and a portion connected to the outlet port of said casing, means for causing the liquid petroleum product to flow from said reservoir through said line and through said casing, the entrained heavier liquid flowing from the reservoir through said line and into the casing with the liquid petroleum product, means in said casing forming an internal chamber having an upper opening positioned to establish communication with the outlet port of said casing, a conduit leading to the lower part of said chamber and having its intake end terminating in said casing adjacent the lower wall thereof, the upper portion of said chamber having a relatively large inlet port through which liquid in the casing flows from outside the chamber to the outlet port, said chamber having a relatively smaller port in its lower portion and communicating with said conduit, a float in said chamber and movable between said lower and upper portions of the chamber, said float being buoyant in the heavier liquid and sinking in the liquid petroleum product, a valve connected to said float and operated thereby for controlling the opening and closing of said outlet port, a main portion of the liquid entering said casing passing into said chamber through said relatively large inlet port and a smaller portion of the liquid entering said casing passing through said conduit into said chamber through said relatively smaller port at a relatively higher rate of travel whereby to cause the float to be moved upwardly in said chamber at a greater rate than the rate of rise of the separated heavier liquid in the casing outside said chamber, and means for discharging the separated heavier liquid from the lower portion of said casing.

6. In a liquid dispensing apparatus, a reservoir for liquid petroleum product which may contain a liquid of greater specific gravity entrained in the liquid petroleum product, a liquid separator comprising a casing having an inlet and an outlet, a dispensing conduit connected with said outlet, means associated with said separator and reservoir for causing the liquid petroleum product to flow from said reservoir through said inlet and into said separator and from said separator through said outlet and said conduit, the entrained liquid of greater specific gravity flowing from said reservoir and into said separator with said liquid petroleum product, said separator being so constructed and arranged as to separate within the casing the entrained heavier liquid from the liquid petroleum product, means forming an auxiliary liquid separating chamber within said casing, said chamber having an opening therein positioned to establish communication with the outlet of said casing, said chamber having a port in its upper portion positioned to pass the liquid petroleum product from said casing into said chamber, the liquid petroleum product passing into said casing through said port flowing through said opening to the outlet of the casing, said chamber having in its lower portion an inlet opening, means operated by the heavier liquid as the level of said heavier liquid in said chamber varies for controlling the opening and closing of said outlet, means in said separator casing for dividing the stream of liquid entering said casing through said inlet into two portions, one a main portion and the other a relatively small portion, the separator being so constructed as to cause the small portion of the stream to be more heavily charged with the entrained heavier liquid than

the main portion of the stream, flow directing means in said casing so positioned as to decelerate the main portion of the stream sufficiently to permit separation of the entrained heavier liquid from the liquid petroleum product as the liquid petroleum product flows toward the inlet port of said chamber, said dividing means being so constructed and arranged as to direct a small portion of the stream to the inlet opening of said chamber at a higher rate than the rate of flow of the liquid petroleum product toward the inlet port of said chamber whereby to cause the heavier liquid separated in the chamber to rise in level at a more rapid rate than the rise in level of the separated heavier liquid in the casing outside of said chamber, and means for discharging from said casing, the separated liquid of greatest specific gravity collected in the bottom thereof.

7. In a liquid segregating system, a reservoir for liquid petroleum product which may contain two entrained liquids of different specific gravities greater than the specific gravity of the liquid petroleum product, a liquid segregator device comprising a casing having an inlet, means associated with said reservoir and device for supplying the liquids from said reservoir to the inlet of said casing, said casing having a discharge port for the liquid petroleum product supplied thereto and means connected to said discharge port for delivering said liquid petroleum product to a point of delivery, said casing having a lower portion for collecting the segregated liquid of greatest specific gravity, the lower portion of said casing having a discharge port for the liquid of greatest specific gravity, means operated by the liquid of greatest specific gravity as the level thereof in said portion of the casing varies for controlling the opening and closing of said last mentioned discharge port to discharge said liquid of greatest specific gravity, means forming a chamber in the upper portion of said casing, a valve for controlling the opening and closing of the discharge port for the liquid petroleum product, a float in said chamber and operatively connected to said valve for controlling said valve, said float being buoyant in the liquids of specific gravity greater than the petroleum product, said casing having its inlet, through which liquid is supplied to said casing, between said upper and lower portions, whereby stratification of the liquids in said inlet tends to result in the liquid of greater specific gravity entering said lower portion of said casing and liquid of lesser specific gravity entering the upper portion thereof surrounding said chamber, and means for conducting a small portion of the stream of liquids entering said casing through said inlet directly to said chamber beneath said float for raising said float to valve closing position in response to the accumulation of the liquid of greatest or intermediate specific gravity in said chamber to one or another predetermined level.

8. In a liquid dispensing apparatus, a reservoir for liquid petroleum product which may contain a liquid of greater specific gravity, a segregator comprising a casing having a lower inlet port and an outlet port at the top of the casing, a dispensing conduit connected with said outlet port, means associated with said segregator and reservoir for causing the liquid petroleum product to flow from said reservoir to said inlet port and into said segregator casing and from said

segregator casing through said outlet port and said conduit, the heavier liquid flowing from the reservoir into said segregator casing with the liquid petroleum product and being entrained therein, means associated with said casing and forming a chamber having an outlet port in communication with said dispensing conduit, a float in said chamber, said chamber being in communication with the inlet port of said casing and having ports to allow the lighter fluid from said casing to flow to said dispensing conduit, a second conduit connected with said last means and terminating in a nozzle located at the lower wall of said casing and adjacent the inlet port thereof to pick up the heavier liquid flowing along said wall, and through which passes into the chamber a portion of the liquid petroleum product and entrained heavier liquid flowing into the inlet port of said casing, said segregator casing and said chamber being each constructed and arranged to separate the entrained heavier liquid from the liquid petroleum product flowing into said casing and chamber through their inlet ports and second conduit respectively, an imperforate portion of said chamber cooperating with said float for causing the heavier liquid to rise in level at a greater rate in said chamber than the heavier liquid rises in level in said segregator casing, means associated with said chamber and operated by the heavier liquid as the level thereof in said chamber varies for controlling the opening and closing of the outlet port of said casing, and means for discharging the separated heavier liquid from the lower part of said casing.

9. In a liquid dispensing apparatus, a reservoir for liquid petroleum product which may contain a liquid of greater specific gravity, a segregator comprising a casing having inlet and outlet ports, a dispensing conduit connected with said outlet port, means associated with said casing and forming a chamber having an outlet in communication with said conduit, said chamber having an inlet, liquid forcing means associated with said reservoir, said conduit and said casing for causing the liquid petroleum product to flow from said reservoir through said inlet port into said casing and from said casing through said outlet port and said conduit, the heavier liquid flowing from the reservoir into said casing with the liquid petroleum product and being entrained therein, said casing being so constructed as to separate the heavier liquid from the liquid petroleum product in said casing, supply means associated with said liquid forcing means and said chamber and comprising a conduit communicating with said chamber inlet and terminating adjacent the lower surface of said inlet port of said casing to supply a portion of the heavier liquid to said chamber through said chamber inlet at a rate such that the ratio of said rate to the volume of the chamber is greater than the ratio of the rate of flow of the heavier liquid into the casing to the volume of the casing, whereby the heavier liquid rises in level in the chamber at a faster rate than in the segregator casing, and means including a control element operated by the heavier liquid as the level thereof in said chamber varies for controlling the opening and closing of said casing outlet port and means for discharging the separated heavier liquid from the lower part of said casing.

DAVID SAMIRAN.
